UNITED STATES PATENT OFFICE.

JOHN H. MACALMAN, OF SOMERVILLE, MASSACHUSETTS, ASSIGNOR TO THE
"LOCOMOBILE" COMPANY OF AMERICA, OF NEW YORK, N. Y.

DESIGN FOR A WAGON-BODY.

SPECIFICATION forming part of Design No. 34,454, dated April 30, 1901.

Application filed January 30, 1901. Serial No. 45,390. Term of patent 14 years.

To all whom it may concern:

Be it known that I, JOHN H. MACALMAN, a citizen of the United States, residing at Somerville, in the county of Middlesex, State of Massachusetts, have invented and produced 5 a new and original Design for Wagon-Bodies, of which the following is a specification, reference being had to the accompanying drawing, forming part thereof.

10 The figure is a view showing my design of wagon-body in perspective.

As shown in the drawing, the leading or material feature of my design consists in a wagon-body having an approximately parallelogram-shaped back or box portion *a*, with a front portion *b* curving upward and outward at *c* in an undulating curve, as shown. The bottom line of the body extends in substantially 15 the same horizontal plane to a point *d* near the

front end, where it takes the upward undulating curve *c*. The top line of the front portion *b* extends in substantially the same horizontal plane to a point *e*, where it curves downward to the horizontal at *f* and upward in a curve *g* to the top of the front of the parallelogram-shaped back portion *a*.

Having described my invention, what I claim as new, and desire to secure by Letters Patent, is—

The design for a wagon-body as herein 20 shown and described.

In testimony whereof I have signed my name to this specification in the presence of two subscribing witnesses.

JOHN H. MACALMAN.

Witnesses:

WM. HENRI IRISH,
J. ARNOLD FANER.
